(57) **CLAIM**

The ornamental design for a slip simulation shoe cover, as shown and described.

DESCRIPTION

FIG. 1 is a perspective bottom view of the slip simulation shoe cover according to the present design;

FIG. 2 is a top view of the slip simulation shoe cover as shown in FIG. 1;

FIG. 3 is a bottom view of the slip simulation shoe cover as shown in FIG. 1;

FIG. 4 is a left side view of the slip simulation shoe cover as shown in FIG. 1;

FIG. 5 is a right side view of the slip simulation shoe cover as shown in FIG. 1;

FIG. 6 is a front view of the slip simulation shoe cover as shown in FIG. 1; and,

FIG. 7 is a rear view of the slip simulation shoe cover as shown in FIG. 1.

The broken lines shown in the drawing disclosure are for illustrative purposes only and form no part of the claimed design.
